UNITED STATES PATENT OFFICE

168,122

HAND OPERABLE PRINTING DEVICE

Jean O. Reinecke, Oak Park, Ill., assignor to The Heyer Corporation, Chicago, Ill., a corporation of Illinois

Application May 5, 1951, Serial No. 15,080

Term of patent 14 years

(Cl. D64—10)

To all whom it may concern:

Be it known that I, Jean O. Reinecke, a citizen of the United States and resident of Oak Park, in the county of Cook and State of Illinois, have invented a new, original, and ornamental Design for a Hand Operable Printing Device, of which the following is a specification, reference being had to the accompanying drawing, forming a part thereof.

Figure 1 is a perspective view of a hand operable printing device showing my new design; and

Fig. 2 is a similar view as observed from the opposite side of the device.

I claim:

The ornamental design for a hand operable printing device, substantially as shown.

JEAN O. REINECKE,
